UNITED STATES PATENT OFFICE

CHARLES L. GEORGE, OF FINDLAY, OHIO, ASSIGNOR TO THE BUCKEYE TRACTION DITCHER COMPANY, OF FINDLAY, OHIO, A CORPORATION OF OHIO

TRENCHING MACHINE

Application filed March 25, 1932. Serial No. 601,209.

This invention relates particularly to trenching machines of the wheel-type.

One object of the invention is the provision of an improved crumbler attachment or shoe, which trails the digging wheel to reclaim the crumbs that accumulate behind the wheel buckets and is automatically adjustable in use about the wheel axis as a fixed center to permit it to rise and fall relative to the digging wheel as it follows any changes, from a straight horizontal line, of the trench bottom, and at the same time to maintain a fixed spacing with respect to the wheel axis. This feature of the crumbler 10 permits digging to the desired depth much more quickly than is possible with machines employing fixed crumblers, and also has a distinct advantage when excavating trenches where the digging wheel must be frequently 15 raised in order to clear obstructions, such as gas, electric and water lines.

Other objects and advantages will be apparent from the following detailed description and from the accompanying drawings 25 illustrating one embodiment of each of the features of the invention, and in which—

Figure 1 is a side elevation of an excavating machine embodying the invention, with the digging wheel in lowered digging position, portions of the machine being omitted. Fig. 2 is a similar fragmentary view of the machine illustrating the action of the crumbler as the digging wheel is lowered to depth in a trench digging operation, the 30 raised position of the wheel and crumbler being shown in dotted lines. Fig. 3 is a fragmentary view of the digging wheel and crumbler illustrating the manner in which the latter follows a trench bottom as the 35 wheel is raised or lowered from normal depth of digging to clear an obstruction, such as a water line. Fig. 4 is an enlarged side elevation of the crumbler and the portion of the frame by which it is carried. Figs. 5 and 6 40 are cross-sections, respectively, on the lines 5—5 and 6—6 in Fig. 4, and Fig. 7 is an enlarged face view of the crumb-gathering portion of the attachment.

Referring to the drawings, 1 designates 50 the main frame of a trenching machine, car-

ried, in the present instance, by tractor units 2 of the apron-type, and itself carrying various power and control units common to machines of this type.

The customary upright frame 3 is provided at the rear end of the frame 1. The digging wheel 4 is carried in the usual or any suitable manner by the vertically swinging frame 5, which at its forward or inner end is provided with hanger arms 6 pivotally 55 suspended from a block 7 guided for vertical sliding movements by the upright 3, as well understood in the art. Vertical adjustment of the inner and outer ends of the wheel-frame is effected by cables 8 and 9 extending 60 over sheaves at the top of the upright from suitable control means 10 on the main frame. All of these features of construction are well understood in the art and need not, therefore, 65 be described in detail. 70

The means for transmitting power to the digging wheel from power means mounted on the main frame 1 comprises a cross-shaft 11 mounted on the main frame forward of the upright 3 and having suitably controlled 75 driven connection with a power unit 12. This shaft may be termed the "drive shaft", as applied to the driving connection between the power unit and digging wheel, and may be the same, both in its mounting and driv- 80 ing, as the corresponding shaft of the drive means now commonly employed. The shaft 11 has a sprocket-wheel 13 fixed to each end thereof, and also has a small wheel or disc member 14 mounted thereon between each 85 wheel 13 and the adjacent end of the casing 15 in which the shaft is mounted. The shaft is longer than the width of the frame 3 so that the members 13 and 14 are disposed beyond its sides. An arm 16 is mounted at its 90 forward end on each disc member 14 for swinging coaxially with the shaft 11 and has its opposite or rear end provided with a yoke 18. A cross-shaft 19 parallels the shaft 11 and is mounted at its respective end por- 95 tions in suitable bearings or openings pro- vided in the ends of the arms of the respective yokes 18. The shaft 19 serves to firmly connect the arm 16, 16, and to cooperate there- 100 with to form a substantially U-shaped frame

for swinging movements about the axis of the shaft 11. A sprocket wheel 21 is mounted on the shaft 19 within each yoke 18 and is connected by a sprocket chain 23 with the respective sprocket wheel 13 on the shaft 11, the shaft 19 is spaced with respect to the customary digging wheel driving shaft 24, mounted on the frame 5, with an arm 25 at each end thereof, which has yoke-connection 26 at its forward end with the shaft 19 in adjacent relation to the respective yoke end of the arm 16, and has its rear end in bearing engagement with the shaft 24. A sprocket-chain 30 connects a sprocket-wheel 29 on each 15 end of the shaft 24 with a respective sprocket-wheel (not shown) mounted on the shaft 19 within the forks of the arms 16 and 25. The shaft 24 has the customary spur-gear driving connection with the rim members of the 20 digging wheel 4.

It is apparent with this form of drive for the digging wheel, that the digging wheel frame may be placed in any position of adjustment relative to the main frame without 25 affecting the efficient driving action of the driving means, and that it eliminates the use of some type of chain slack device customarily employed.

The crumbing feature of the invention 30 comprises a shoe 35 carried at the lower end of an arcuate arm 36, which extends up through a guide 37 provided at the rear end of the digging wheel frame 5 and is adapted to have free longitudinal sliding adjusting 35 movements therein. The arm 36 and shoe are disposed at the rear peripheral side of the digging wheel 4, and both the curvature of the arm and its arc of adjusting movements are concentric to the axis of the digging wheel, so that the shoe 35 is maintained in fixed spaced relation to the digging wheel axis irrespective of the position of the shoe relative to the frame.

The plane of the bottom surface of the 45 shoe 35 is tangent to a circle defined by the cutting noses of the digging wheel buckets, so that the shoe will ride substantially flat on the bottom of a trench dug by the wheel irrespective of whether or not such bottom defines a straight horizontal course. The shoe rises and falls with respect to the bottom line of the digging wheel to suit the elevation, relative to the wheel bottom, of the portion 50 of the trench bottom on which the shoe rests, and the shoe at the same time maintains a 55 fixed spacing with respect to the wheel axis. This is important in connection with the use of a wheel when digging a course which is inclined to or irregular with respect to a horizontal, such, for instance, as occurs when a digging wheel, while digging, is moving down to the desired depth, as indicated in Fig. 2, or when raised and lowered in passing over an obstruction, such, for instance, as a water, 60 gas or electric conduit 38, as shown in Fig.

3. With the type of crumber heretofore employed, in which the shoe member thereof maintains a fixed relation to the wheel-carrying frame, it is necessary to have the digging take a more gradual incline in lowering to or 70 raising from a desired digging depth, due to engagement of the stationary shoe with the trench bottom.

The arm 36 of the crumber attachment is, 75 in the present instance, of skeleton form, being composed of front and back plates 39 curved to the form of the arm and having their edges turned toward each other to form flanges to which respective sets of spacing bars 40 are secured.

The guide 37 for the crumber arm is curved to conform to the curvature of the arm and comprises angle-iron corner guide-strips 41 secured together by suitable cross-pieces 42, and the guide, as an entirety is carried by the 80 cross-bars 43 and 44 secured to the rear end of the frame 5 and connecting the transversely spaced longitudinal members thereof. The crumber shoe 35 is pivoted to the lower 85 end of the frame near its inner edge, as at 45, and has its rear end adjustably connected to the lower rear end portion of the arm 36 by bolts 46. These bolts, in the present instance, 90 coact with a cross member 47 connecting respective side plates 48 secured to the lower 95 end of the arm. The nose of the crumber comprises a plate 49, which is supported by the forward end of the shoe 35 and extends rearwardly and upwardly to a point where it 100 meets with the curved plate 50 that extends a 105 desired distance up the forward side of the arm. The nose 49 and plate 50 are provided at their side edges with extension plates 51 in bolt and slot connection therewith, so that the effective width of the crumber may be 110 broadened or narrowed to suit the width of the trench being dug, or the size of the 115 buckets employed on the digging wheel.

It is apparent that in the use of a trenching machine equipped with my crumber attachment, such attachment will automatically 120 rise or fall relative to the digging wheel frame to accommodate itself to the height of the trench bottom relative to the lower edge of the digging wheel and at the same time will 125 maintain a fixed spacing with respect to the digging wheel axis. It is also apparent that the shoe will maintain an approximately constant parallel relation to the bottom portion 130 of the trench with which it coacts, irrespective of whether or not the wheel is maintaining a constant level in its digging operation, or is moving upward or downward relative thereto. This is illustrated by Figs. 2 and 3.

I wish it understood that my invention is 135 not limited to any specific construction, arrangement or form of the parts, as it is capable of numerous modifications or changes without departing from the spirit of the claims.

Having thus described my invention, what 140

I claim as new and desire to secure by United States Letters Patent is:

1. In a wheel-type trenching machine, a digging wheel, a carrying frame therefor, and a crumber trailing the digging wheel and adjustably carried by the frame for free arcuate self-adjusting movements coaxial with the wheel axis.
  2. In a trenching machine, the combination with a digging wheel, of a crumber trailing the wheel, and means maintaining the crumber in fixed spaced relation to the wheel axis while permitting free arcuate movements of the crumber about such axis in response to variations in the level of the trench bottom.
  3. In an excavating machine, the combination with a digging wheel, of a crumber trailing the wheel and having an arcuate carrying arm, and means engaging the arm to permit it to have free longitudinal gravity-controlled adjusting movements and maintaining the crumber in constant spaced relation to the wheel axis.
  4. In an excavating machine, the combination with a digging wheel and the carrying frame therefor, of a crumber trailing the wheel and adapted to ride freely on the bottom of a trench being dug by the wheel, an arcuate carrying arm projecting from the crumber, the arc of which is concentric to the wheel axis, and means carried by the frame for coaxing with the arm to guide the arcuate adjusting movements of the crumber about the wheel axis.
  5. In a trenching machine, the combination with a digging wheel and its carrying frame, of an arcuate arm disposed at the rear of the wheel periphery and concentric to its axis, connection between said arm and frame permitting free longitudinal movements of the arm about the wheel axis, a crumber attached to the lower end of the arm and including a shoe adapted to ride freely on the bottom of a trench being dug by the wheel, irrespective of changes in the inclination of the trench bottom.
  6. In a trenching machine, a digging wheel, a frame in which the digging wheel is mounted, and a crumber trailing the digging wheel and mounted for free and independent gravity-controlled movement up or down with reference thereto, in response to changes in the inclination of the trench bottom.
- 55 In testimony whereof I have hereunto signed my name to this specification.

CHARLES L. GEORGE.
